UNITED STATES PATENT OFFICE.

GEORGE LEHBERGER, OF NEWARK, NEW JERSEY.

FLYING-MACHINE.

1,009,157.

Specification of Letters Patent. Patented Nov. 21, 1911.

Application filed October 4, 1909. Serial No. 520,896.

To all whom it may concern:

Be it known that I, GEORGE LEHBERGER, a citizen of the United States, residing in the city of Newark, county of Essex, and State 5 of New Jersey, have invented certain new and useful Improvements in Flying-Machines, of which the following is a full, clear, and exact description, such as will enable others skilled in the art to which it 10 pertains to make, construct, and use the same.

My invention relates to flying machines, and particularly to that type of flying machine commonly called "aeroplane," which 15 are provided with extended surfaces, so that when driven at considerable speed, they will be buoyed or sustained by pressure of the air.

My invention has for an object, to so construct 20 an aeroplane that it will rise more easily from the ground, be sustained in the air at a less speed than has heretofore been possible, and be governed and operated more easily.

More particularly, my invention has for its object, to construct a flying machine of 25 this type comprising a skeleton frame, preferably of oblong form and made of a light frame of wood or light metal, and having a supporting plane mounted on the top of 30 said frame, of a pair of planes pivotally secured to the edge of the supporting plane and extending outwardly from each side of 35 said frame, and provided with means whereby said planes may be simultaneously flexed to the same extent in opposite directions. A tail-piece is conveniently secured to the frame and extending rearwardly therefrom, and a vertical rudder and means for operating 40 said rudder, are also provided. Attached to the upper front end of the frame of the apparatus, and preferably in line with the tail-piece, I provide another light and preferably a detachable frame, in which 45 is mounted a front horizontal rudder having a flexible body. By means of tiller ropes, cables, or other well-known connections, the tail-piece, horizontal and vertical rudders, as well as the side planes may be manipulated 50 to direct the course of the apparatus.

In the car supported from the frame, a mo-

tor is conveniently located, to which are operatively connected front and rear propellers, and means are furnished for moving the front propellers in various directions. 55

The invention is clearly illustrated in the accompanying drawings, in which—

Figure 1 represents a plan view of my improved apparatus. Fig. 2 represents a front end elevation of the same, in which the front horizontal rudder has been removed. Fig. 3 represents a sectional plan view on an enlarged scale, taken on lines $\alpha-\alpha$ of Fig. 2. Fig. 4 represents a sectional side elevation on an enlarged scale of my improved apparatus; and Figs. 5 and 6 represent views of the steering wheel with its attached parts. 65

Similar letters of reference refer to like parts throughout the specification and drawings. 70

In the drawings, a designates the car body or frame preferably rectangular in shape, made of suitable and light material, such as wood, or tubular steel, of skeleton structure, adapted to present a minimum resistance 75 surface to the air during the ascension and propulsion of the machine, the same comprising upper and lower frames b which are spaced apart and rigidly held in this relation by a series of vertical sustaining posts 80 c . Secured to the lower frame on a suitable platform d is a motor e , the driving shaft e' of which is provided with chain wheels f in alinement with the chain wheels f' on the propeller operating shafts g , and over 85 which drive chains g' are adapted to be conducted. Any suitable motive power may be employed for driving the propeller operating shafts g . These propeller operating shafts which operate the propellers h^2 are 90 located approximately at the corners of the frame, and extend outwardly at right-angles to and beyond the frame of the apparatus. The propeller operating shafts g are surrounded by sleeves h which are mounted 95 in suitable bearings h' secured to the frame of the apparatus. To the outer ends of the sleeves are secured the U-shaped brackets i within which are mounted in suitable bearings the lateral propeller shafts j , to which 100 are secured the propellers h^2 , each propeller being provided with a series or plurality of

curved planes or blades. These propellers give the car its forward propulsion.

Upon the lateral propeller shafts *j* are secured bevel gears *k* which mesh with the bevel gears *l* secured to the propeller operating shafts *g*. By means of this connection, the propellers may be revolved by rotating the propeller operating shafts. The propeller operating shafts *g* are rotated by 10 means of any suitable motor located within the frame of the apparatus and connected with the shafts. Upon the outer ends of the motor shaft *e'* are shown chain wheels *f* which carry chains *g'* connecting them with 15 chain wheels *f'* mounted upon the propeller operating shafts *g*. The sleeves *h* surrounding the front propeller operating shafts have chain wheels *m* or pulleys mounted thereon, connecting with a steering wheel 20 shaft or other suitable means, by means of which, the position of the front propellers may be controlled. If it is desired to progress forward, the front propellers would be adjusted in a vertical position. In rising 25 from the ground, the propellers would be in an angular position tilted to the rear and upward. In descending, they would be in an angular position tilted to the front and downward.

Upon the upper portion of the frame of the apparatus, is attached a horizontally curved plane *n* preferably of oblong form, and made of a light frame of wood, or light metal and covered with canvas, silk or other 30 suitable material. Hinged to the sides of the frame work of the curved plane *n* at *n'*, and extending downwardly and outwardly from the said plane *n*, are a pair of similar planes *o*, the inner edges of which are secured to the frame of the machine as at *n''*, thus providing means for collapsing the 35 planes and laying them against the sides of the frame of the machine. The planes *o* are arranged as described, for the purpose 40 of providing means whereby said planes *o*, when the machine is not in actual use, can be disconnected from the frame of the machine at *n''*, and swung around the hinge *n'*, so that the parts of the planes *o* located 45 between the hinge *n'* and the point *n''* where they are secured to the frame of the machine, can be brought to lie against the under side of the plane *n*. By this operation, the extreme outer edges of the planes *o* 50 are brought closer together, thereby enabling the machine to be placed in a shed of comparatively small dimensions. These air planes *o* extend beyond the sides of the apparatus and are to be used for controlling 55 the vertical position of the apparatus. By suitably arranged means to be hereinafter described, the marginal edges of the air planes on both sides of the apparatus may be simultaneously flexed to the same extent 60 in opposite directions, when it is desired to

elevate the apparatus while in motion, or to make a curve. A vertical rear rudder *p*, so supported as to turn around a vertical axis, is pivoted to the rear end of the frame of the apparatus between the same and has 70 means extending within the apparatus by which it is controlled, thereby providing for the steering of the same.

Attached to the upper rear end of the frame of the apparatus, extending outwardly and rearwardly from the same, is another light frame *q* having secured thereon, a horizontal plane *q'* called the tail-piece, having a flexible body of the same material as the planes heretofore described, but 75 differing in form. Attached to the upper front end of the frame of the apparatus, and preferably in line with the tail-piece *q'* is another light frame *r* in which is mounted a front horizontal rudder *r'* having a flexible body. The tail-piece *q'* and horizontal rudder *r'* form a part of the supporting system and serve to control the motion for the purpose of causing the apparatus to rise or fall or to drive it horizontally. By means of tiller ropes, cables, or other well-known connections, the horizontal and vertical rudders, as well as the side planes and front propellers may be 80 turned or manipulated to direct the course 85 of the apparatus.

The different planes, tail-piece, horizontal and vertical rudders are formed by stretching cloth, or other suitable fabric over a frame composed of a series of inner supporting ribs or braces, preferably constructed of wood having the necessary strength combined with lightness and flexibility. This construction gives to them a surface which has 90 very great strength to withstand lateral and 95 longitudinal strains, at the same time capable of being bent or twisted in the desired manner.

The horizontal rudder as will be seen, is 100 pivotally secured in the frame extending from the forward end of the machine, and has rigidly secured to the short sides of its frame in any convenient manner, a lever *r''*, one arm of which extends above and the other arm of which extends below the plane 105 of the rudder, and to which arms are secured cables, whereby the rudder may be adjusted to any desired angle and simultaneously flexed or bent, whereby the longitudinal edges near their extremities may be inclined 110 downward and rearward and upward and forward, or vice versa.

The frame of the car is provided with wheels *s* to normally sustain the apparatus, which wheels in practice, will be equipped with suitable buffer springs to cushion the shock on alighting after flight, said buffer springs, because they are common and form 115 no part of this invention, not being shown.

Conveniently mounted upon the cross 120

piece s^2 , and in front of the seat s' , is a bracket s^3 , to which is pivotally secured by means of the pivot pin v , the bearing s^4 for the reception of the steering wheel shaft t , to which is secured the steering wheel t' . Rigidly secured to the wheel shaft t above and below the bearing s^4 , are the four armed spiders t^2 , to which are secured the cables or ropes for manipulating the horizontal and vertical rudders, the side planes and the front propellers.

From an inspection of Figs. 3 and 4, it will be seen that the upper arms of the lever r^2 which project above the horizontal rudder r' , are by means of cables or ropes (which are indicated by dotted lines), connected to the side arms u of the upper spider t^2 , and that the lower arms of the lever r^2 which project below the horizontal rudder r' are by means of cables or ropes which cross each other at r^3 connected to the side arms u of the lower spider t^2 . From the manner in which the upper and lower levers r^2 of the horizontal rudder r' are connected by means of the cables or ropes to the side arms u of the upper spider t^2 , it will be evident that when the steering wheel with its connected shaft and spiders is moved forward, or backward around the pivot pin v , the angle of inclination of said horizontal rudder r' will be changed, but if the wheel t' with its attached arms and spiders is turned in either direction toward the right or left, as distinguished from being moved forward and backward, the cables connecting the levers r^2 of the horizontal rudder with the arms of the spider, will cause the longitudinal edges of said rudder, near their extremities, to be flexed downward and rearward, and upward and forward, or vice versa. The vertical rudder p has secured to it a cable or rope passing over suitable pulleys conveniently arranged upon the frame of the machine, said cable or rope being secured to the rear arm u of the upper spider t^2 .

The chain wheels m secured to the sleeves h which surround the front propeller operating shafts, are provided with a short piece 50 of chain, the upper ends of which are connected with cables or ropes, which are similarly connected to the side arms u of the upper spider t^2 , while the lower ends of the chain are connected with cables or 55 ropes, which are crossed and secured to the side arms u of the lower spider t^2 in practically the same manner as the cables which connect the upper and lower arms of the lever r^2 of the horizontal rudder r' .

60 The front edges of the side planes near their extremities, are connected by means of the cable passing over a pulley mounted on the support v' , said cable being secured to the front arm u of the lower spider t^2 . It 65 will thus be seen that when the steering

wheel is turned in either direction, the cable which passes over the pulley mounted upon the support v' , and which is connected to the front edges of the side planes near their extremity, and which cable is also connected to the arms u of the spider t^2 , will flex the extreme outer edges of said side planes o in opposite directions to the same extent. 70

The operation of my apparatus is as follows: The apparatus will of course be 75 started on the wheels of the car. The operator after taking his position in the car starts the motor so as to rotate the propellers in the direction indicated by the arrows, the propellers and the horizontal rudder being in the position as shown in Fig. 3. When it is desired to rise, the steering wheel with its connected shaft and spiders, is slightly moved forward around the pivot pin v , thereby manipulating the above described connecting cables, and simultaneously changing the angle of the front propellers and the horizontal rudder, which will be preferably set at a considerable inclination tilted to the rear and upward. The 80 angle will depend upon the condition of the wind and also upon the velocity of the machine. The angle of the rear propellers is not changed as they are designed to always remain in a vertical position as shown. 85 When it is desired to take a curve, the steering wheel is slightly turned in either direction, thereby manipulating the described connecting cables, thus simultaneously changing the position of the rear vertical 90 rudder and flexing the edges of the side planes on both sides of the apparatus to the same extent in opposite directions, and also flexing the longitudinal edges of the front 95 horizontal rudder near their extremities 100 downward and rearward, and upward and forward, or vice versa. 105

In Fig. 1 of the drawings, I have shown in dotted lines, a square opening in the side planes o nearest the frame of the machine. 110 This opening is also shown in full lines in Fig. 4, and is adapted to permit the air to pass through said opening and out through the supporting plane n .

From the above description, it will be apparent that I have produced an aerial apparatus possessing the features of advantage enumerated as desirable, and I wish it to be understood that I do not desire to be limited to the exact details of construction shown 115 120 and described, as obvious modifications will suggest themselves to those skilled in the art.

I claim:

1. In a flying machine, the combination with a frame, a supporting plane mounted 125 on the top of said frame, of a pair of planes extending outwardly from each side of said frame, and being partially overlapped by the supporting plane, a car supported from said frame, and connections controlled from 130

said car, whereby the outer edges of said pair of planes may be simultaneously flexed to the same extent in opposite directions.

2. In a flying machine, the combination 5 with a frame, a supporting plane mounted on the top of said frame, of a pair of planes extending outwardly from each side of said frame and being partially overlapped by the supporting plane, means whereby the 10 outer edges of said planes may be simultaneously flexed to the same extent in opposite directions, a tail-piece extending rearwardly from said frame, a vertical rudder, means for operating said rudder, a horizontal 15 rudder extending forwardly from said frame, a car supported from said frame, a motor supported in said car, propellers operatively connected to said motor and means for moving said propellers in various 20 directions.

3. In a flying machine, the combination 25 with a frame, a supporting plane mounted on the top of said frame, of a pair of planes pivotally secured to the supporting plane and being partially overlapped by the supporting plane, a plane secured to the rear of said frame, a horizontal rudder pivotally secured to the front of said frame, a car supported from said frame and connections 30 controlled from said car, whereby said front horizontal rudder and the outer edges of the side planes may be flexed so as to present to the atmosphere different angles of incidence.

4. In a flying machine, the combination 35 with a frame, a horizontally curved supporting plane mounted on the top of said frame, a pair of similarly curved planes pivotally secured to the supporting plane, and partially overlapped by said supporting plane, a car supported from said frame, and connections controlled from said car, whereby the marginal edges of said pair of planes may be simultaneously flexed to the same extent in opposite directions.

45 5. In a flying machine, the combination with a frame, a supporting plane mounted on the top of said frame, of a pair of side planes extending outwardly from each side of said frame and being partially overlapped by the supporting plane, a plane extending rearwardly from said frame, a horizontal rudder extending forwardly from said frame, and lying substantially in the same plane with said rearwardly extending 55 plane, a car supported from said frame, and connections controlled from said car, whereby said side planes and rudder may be flexed simultaneously in various directions.

6. In a flying machine, the combination 60 with an aeroplane, of a pivotally arranged horizontal flexible rudder provided with arms extending upwardly and downwardly therefrom and means connecting said arms for flexing the longitudinal edges of said rudder by 65 moving said arms in opposite directions.

7. In a flying machine, the combination with an aeroplane, of a horizontal flexible rudder pivotally secured to the front of the machine, and means secured to the transverse edges of said rudder and connected with means located within the machine for flexing the longitudinal edges of said rudder by moving said means secured to the transverse edges of said rudder in opposite directions.

8. In a flying machine, the combination 75 with an aeroplane, of a horizontal flexible rudder centrally and pivotally secured to the front of the machine, and provided with upwardly and downwardly extending arms and means located within the machine and connecting said arms for flexing the longitudinal edges of said rudder by moving said arms in opposite directions.

9. In a flying machine, the combination 80 with a frame, a supporting plane mounted on the top of said frame, of a pair of planes extending outwardly from each side of said frame, a vertical rudder pivotally secured to the rear of said frame, a horizontal rudder extending forwardly from said frame, and means located within said frame for simultaneously changing the position of the vertical rudder and flexing the marginal edges of the side planes on both sides of the 85 machine to the same extent in opposite directions and also flexing the longitudinal edges of the horizontal rudder near their extremities downward and rearward and upward and forward.

10. In a flying machine, the combination 90 with a frame, a supporting plane mounted on the top of said frame, of a pair of planes extending outwardly from each side of said frame, a vertical rudder pivotally secured to the rear of said frame, a horizontal rudder extending forwardly from said frame, propellers secured to the sides of said frame, and steering means pivotally located within said frame, the forward movement of which 95 will simultaneously change the angular position of the propellers, and of the vertical and horizontal rudders and simultaneously flex the edges of the side planes on both sides of the machine to the same extent in opposite directions and the longitudinal edges 100 of the horizontal rudder near their extremities.

11. In a flying machine, the combination 105 with a frame, two horizontally curved planes extending outwardly from and pivotally secured to said frame, the outer portions of which are capable of being simultaneously flexed to the same extent in opposite directions, means located within the frame for simultaneously flexing said outer portions and a supporting plane mounted on the top of said frame, said plane overlapping the 110 said two horizontally curved planes.

12. In a flying machine, the combination 115 with an aeroplane, of a horizontal rudder

pivottally secured at its ends in a frame to the front of the machine, and means for flexing the longitudinal edges of said rudder by moving said means in opposite directions.

- 5 13. In a flying machine, the combination with a frame, two horizontally curved planes extending outwardly from and pivottally secured to said frame, the outer portions of which are capable of being flexed to the same extent in opposite directions, a horizontal rudder pivottally secured in a frame to the front of the machine and means located within the frame for simultaneously flexing the outer portions of the curved planes and flexing the longitudinal edges of the horizontal rudder near their extremities downward and rearward and upward and forward.
- 10 14. In a flying machine, the combination with a frame, two horizontally curved planes extending outwardly from and pivottally secured at their inner portions to said frame, the outer portions of which are capable of being flexed to the same extent in opposite directions, means located within the frame for simultaneously flexing said outer portions and a supporting plane mounted on the top of said frame, said plane overlapping the said two horizontally curved
- 15 20 25 30 planes.

15. In a flying machine, the combination with a frame, two horizontally curved

planes extending outwardly from and pivottally secured at their inner portions to said frame, the outer portions of which are capable of being flexed to the same extent in opposite directions, a horizontal flexible rudder pivottally secured in a frame to the front of the machine and means located within the frame for simultaneously twisting the outer portions of the curved planes and flexing the longitudinal edges of the horizontal rudder near their extremities downward and rearward and upward and forward.

16. In a flying machine, the combination with a frame, two horizontally curved planes extending outwardly from and pivottally secured at their inner portions to said frame, the outer portions of which are capable of being flexed to the same extent in opposite directions, a horizontally curved supporting plane mounted on the top of said frame and partially overlapping said planes and means located within the frame for simultaneously flexing the outer portions of the curved planes extending from said frame.

This specification signed and witnessed this 1st day of October 1909.

GEORGE LEHBERGER.
